Primary Examiner — Kendra Leslie Hamilton*Assistant Examiner* — Michael Hoffman(74) *Attorney, Agent, or Firm* — Sterne, Kessler, Goldstein & Fox P.L.L.C.(57) **CLAIM**

The ornamental design for a device for surgical irrigation as shown and described.

DESCRIPTION

FIG. 1 is a front, left perspective view of a device for surgical irrigation showing the claimed design;

FIG. 2 is a left side view thereof; and,

FIG. 3 is a front cross-sectional view thereof taken along line 3-3 of FIG. 2.

The broken lines in the figures show portions of the device for surgical irrigation that form no part of the claimed design.

1 Claim, 3 Drawing Sheets(56)
